UNITED STATES PATENT OFFICE.

WILLIAM JAMES DE LA MARE, OF DES MOINES, IOWA.

AIRSHIP.

1,221,841.

Specification of Letters Patent. Patented Apr. 10, 1917.

Application filed September 2, 1915. Serial No. 48,628.

To all whom it may concern:

Be it known that I, WILLIAM J. DE LA MARE, citizen of the United States of America, and resident of Des Moines, Polk county, 5 Iowa, have invented a new and useful Airship, of which the following is a specification.

The object of this invention is to provide an improved construction for dirigible air 10 ships.

A further object of this invention is to provide improved means for raising an air ship to a higher elevation by direct upward travel.

15 A further object of this invention is to provide an improved manner of mounting a freight and passenger car relative to the body of the air ship.

My invention consists in the construction, 20 arrangement and combination of elements hereinafter set forth, pointed out in my claims and illustrated by the accompanying drawing, in which—

Figure 1 is a side elevation of my improved air ship. Fig. 2 is a bottom plan and Fig. 3 a top plan of the same. Fig. 4 is an end view of the air ship, on an enlarged scale. Fig. 5 is a central longitudinal section of a portion of the air ship, on a 30 further enlarged scale.

In the construction of the air ship as shown a frame is composed of suitable members 10 and is covered with plates 11, preferably of aluminum, to form a body or gas 35 bag, which is relatively long and narrow, being preferably about two hundred feet long, seventy-five feet high and sixteen feet wide at its widest part. The body is also so arranged and constructed as to be sharp 40 pointed at both ends and at its top and bottom, so that when in motion it cuts the air like a knife, and is capable of attaining a high rate of speed, the friction with the air thus being reduced to a minimum. The

45 aluminum plates 11 of the lower portion of the body comprising a distance of approximately the lower two-thirds of said body, are covered with steel armor plates 12. A combined freight and passenger car is 50 mounted in the lower portion of the body and is formed with a deck or floor 13 and ceiling 14 separating the car from the gas-containing portion of the body. The deck 13 is approximately seventy feet long, and 55 occupies the entire width of the body at a

height of about eight feet above the lower line of said body, which tapers to a knife edge therebeneath. Thus the car and its contents are effectively protected from attack from beneath, as the tapering sides of 60 the lower part of the body will cause any projectiles cast against it to glance off, as they are reinforced by the steel armor plates 12. The sides of the car, between the deck 13 and ceiling 14, are provided with shuttered windows 15. Doors 16 provide means of entrance and exit relative to the car. A plurality of prime movers 17, 18, 19, 20, in this instance four in number and preferably being internal combustion engines, are 70 mounted and spaced apart on the deck 13, and drive shafts 21, 22, 23, 24 are journaled for rotation in the car and adapted to be driven respectively by said prime movers. A plurality of horizontal propellers 25, 26 75 are mounted on and fixed to vertical shafts 27, 28 projecting from the bottom of the body of the machine, and said propellers preferably are arranged in two rows, one on each side of the lower line of said body, and 80 are in this instance eight in number in each of said rows. The propeller shafts 27, 28 are connected to and adapted to be driven by the drive shafts 22, 23 respectively. The shafts 27, 28 are journaled for rotation in 85 bearing brackets 29 fixed to and projecting laterally from the sides of the body above the lower knife edge thereof. The propellers 25, 26, which are here shown conventionally, are of the accepted type except that 90 they are arranged for rotation on vertical axes, and it is their function, working together, to drive the machine upwardly in a direct line and on an even keel. Vertical propellers 30, 31 are mounted on and fixed to 95 shafts 32, 33 respectively, at opposite ends of the body or gas bag. The propellers at each end preferably are arranged in two vertical rows, one on each side of the tapering ends of the body and spaced therefrom, and are 100 designed to drive the machine selectively in opposite directions as desired, without turning it around. The propeller shafts 32 are connected to and adapted to be driven by the prime mover 17, and the propeller shafts 105 33 are connected to and adapted to be driven by the prime mover 20, said prime movers being located at opposite ends of the deck 13 and adjacent the propellers which they drive. The propeller shafts 32, 33 are jour- 110

naled for rotation in bearing brackets 34, 35 fixed to and projecting laterally from the sides of the body, and suitably braced thereto.

5 The interior of the body of the device is divided into a plurality of gas compartments 36 (see Fig. 5), and each of said compartments preferably is not more than twenty feet in any dimension. A plurality 10 of gas generators 37, 38 of common form, in this instance two in number, are mounted in the lower part of the body just above the ceiling 14 of the car, and are designed to generate a suitable gas, lighter than air, 15 and supply it to the various compartments 36 through valve-controlled pipes 39. The gas compartments 36, which are of gas-tight construction, are also provided with outlet pipes 40 leading to vents 41 in the 20 top of the body, and provided with valves operated by cables (not shown) leading to the deck 13. Thus gas may be permitted to escape from certain of the compartments as desired, particularly in the operation of 25 causing the machine to assume a lower altitude. Pressure gages 43 are mounted in the car and are connected to the various gas compartments 36, so that the operator may determine at any time the pressure of 30 gas therein and control the same as desired.

A plurality of circular wells such as 45 are formed on the median line of the body and between the gas compartments thereof, 35 and lead from the ceiling 14 of the car to the top of the body, where they communicate with circular platforms 44 mounted on the top of the device. In this instance the wells 45 and platforms 44 are three in 40 number, but any desired number may be employed. In each well 45 is formed a circular staircase 46 by which access may be had from the car to the platforms, a portion of one of these stairways being shown 45 in Fig. 5. A folding or flexible ladder such as 47 leads from the deck 13 to the lower end of each staircase 46, thus conserving space in the car. A gun or cannon 48, of any suitable type and caliber, is mounted 50 on each of the platforms 44, and said guns are swiveled so that they may be pointed in any direction for effective use.

Rudders 49, 50 are pivoted on vertical axes at opposite ends of the body and are 55 connected by suitable cables 51, 52 to the car, from which they are selectively employed by the operators for steering the device, depending on which set of vertical

propellers is being employed at a given time.

Spaced ground wheels 53, 54 are mounted beneath the device, and each of said ground wheels is carried by a fork 55 connected slidingly to the body, and a coil spring 56 is mounted on each of said forks between the body and the respective ground wheel 53 or 54, thereby cushioning the device on said wheels and preventing injury to any of the parts when said wheels come in contact with the ground.

I have designed this machine to carry twenty-five men and seven to nine tons of explosive matter, together with sufficient fuel, gas-making material and provisions that it may stay in the air for a continuous period of twenty-six days. I estimate that the device so constructed will attain a speed of seventy-five miles per hour in vertical movement, and one hundred and fifty miles per hour in horizontal travel.

Its further advantages and conveniences will be readily apparent to those familiar with machines of this kind.

I claim as my invention—

1. An air ship, comprising a gas-containing body, said body being formed of a frame covered with plates, said body tapering to a knife edge at its top, bottom and both ends, together with propelling and steering means for said body.

2. An air ship, comprising a gas-containing body, said body being attenuated to a bevel edge at its top, bottom and both ends, a set of vertical propellers mounted at each end of said body and adapted for selective operation to drive said body in opposite directions, a rudder mounted at each end of said body, a set of horizontal propellers mounted beneath said body and adapted to propel the same upwardly, and means for selectively operating said sets of propellers.

3. An air ship, comprising a gas-containing body, said body being attenuated to a bevel edge at its top, bottom and both ends, a set of vertical propellers mounted at each end of said body, a rudder mounted at each end of said body, a set of horizontal propellers mounted beneath said body, and means for selectively operating said sets of propellers.

Signed by me at Des Moines, Iowa, this 25th day of August, 1915.

WILLIAM JAMES DE LA MARE.
